(57) **CLAIM**

The ornamental design for a display screen or a portion thereof having an animated graphical user interface for an isometric view of an abstraction of a system platform, as shown and described.

DESCRIPTION

FIG. 1 is a front view of a display screen or a portion thereof having an animated graphical user interface showing a first image in a sequence showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof; and,

FIG. 12 is a twelfth image thereof.

The broken lines showing the display screen or portion thereof form no part of the claimed design.

In a first embodiment, the appearance of the transitional image sequentially transitions between images shown in FIGS. 1-12. In a second embodiment, the appearance of the transitional image sequentially transitions between images shown in FIGS. 12-1. In a third embodiment, the appearance of the transitional image sequentially transitions between images shown in FIGS. 1-7. In a fourth embodiment, the appearance of the transitional image sequentially transitions between images shown in FIGS. 7-1. In a fifth embodiment, the appearance of the transitional image sequentially transitions between images shown in FIGS. 5-12. In a sixth embodiment, the appearance of the transitional image sequentially transitions between images shown in FIGS. 5-12. In a seventh embodiment, the appearance of the transitional image sequentially transitions between images shown in FIGS. 1-12. In an eighth embodiment, the appearance of the transitional image sequentially transitions between images shown in FIGS. 12-1. In a ninth embodiment, the appearance of the transitional image sequentially transitions between images shown in FIGS. 1-7. In a tenth embodiment, the appearance of the transitional image sequentially transitions between images shown in FIGS. 7-1. In an eleventh embodiment, the appearance of the transitional image sequentially transitions between images shown in FIGS. 5-12. In a twelfth embodiment, the appearance of the transitional image sequentially transitions between images shown in FIGS. 5-12.

(Continued)

12-5. The process or period in which one image transitions to another image, for any of the embodiments, forms no part of the claimed design.
